CLAIM

The ornamental design for a fastener applying press, as shown and described.

DESCRIPTION

FIG. 1 is a top view of a fastener applying press showing my new design;

FIG. 2 is a side elevation of a fastener applying press showing my new design;

FIG. 3 is a bottom view of a fastener applying press showing my new design;

FIG. 4 is a left-hand end view (having reference to FIG. 2) of a fastener applying press showing my new design;

FIG. 5 is a right-hand end view (having reference to FIG. 2) of a fastener applying press showing my new design; and, FIG. 6 is a side elevation taken from the opposite side from that of FIG. 2 of a fastener applying press showing my new design.

The top portion of the handle has been removed for ease of illustration in FIGS. 3-6.
